UNITED STATES PATENT OFFICE

2,012,325

MANUFACTURE OF SHOES

Max W. Tetlow, Boston, Mass., assignor to United
Shoe Machinery Corporation, Paterson, N. J.,
a corporation of New Jersey

Application October 30, 1933, Serial No. 695,823

29 Claims. (Cl. 12—142)

This invention relates to improvements in shoes and the manufacture thereof and is illustrated herein particularly with respect to cement lasting.

It is an object of the present invention to provide an improved method of manufacturing shoes characterized by the elimination of lasting tacks or staples so that the entire shoe bottom, or at least the shank portion and forepart of the shoe, when lasted and ready for the attachment of its outsole, will be free from metallic fastenings. As the outsoles of such shoes are attached either by stitching or by cement my improved method provides for the manufacture of shoes the shanks and foreparts of which are free from metallic fastenings.

My invention, in various of its aspects, comprises not only the novel method referred to above but includes also a shoe the upper of which is secured in lasted relation to the insole in accordance with my invention, and improved insoles and shoe uppers prepared as hereinafter described to facilitate the practice of the method of my invention. As herein disclosed the marginal portion of the shoe upper, or of one or more of its layers, is composed of threads of a substance which is soluble in an organic solvent, for example threads of a cellulose ester or ether such as cellulose acetate, or a strip of such material is secured, preferably but not necessarily by stitching, to the marginal portion of the upper or to the marginal portion of the insole. This soluble material is treated with an organic solvent, for example acetone, thereby forming cement. The shoe upper is worked into lasted relation to an insole and last with this cement between the marginal portion of the exposed surface of the insole and the overlasted portion of the shoe upper, the upper being held in lasted relation, for example by tacks or staples, while the cement sets. After the cement has set the tacks or staples are removed.

It will be apparent that the details of the method outlined above may be varied to a considerable extent without departing from my invention, wherefore the following specification and the accompanying drawings should be taken in an illustrative rather than in a restrictive sense.

With the above and other objects in view the invention will now be described with reference to the accompanying drawings and pointed out in the claims.

In the drawings,

Fig. 1 is a perspective view illustrating the manufacture of a shoe in accordance with my invention and showing a shoe and its insole assem-

bled upon a last with its upper secured in pulled-over condition;

Fig. 2 is a perspective view of the same shoe after it has been side lasted in accordance with my invention;

Fig. 3 is a longitudinal sectional view through the toe portion of the shoe after the toe has been lasted;

Fig. 4 is a perspective view illustrating the lasting of the ends of the shoe with the aid of a bed lasting machine;

Fig. 5 is a perspective view of the shoe after the completion of the lasting;

Fig. 6 is a transverse sectional view, on a much enlarged scale, of a portion of the upper, insole and outsole of the completed shoe;

Figs. 7 and 8 are perspective views, taken after the pulling over and side lasting operations respectively, illustrating a variation in the practice of my invention;

Figs. 9 and 10 are perspective views showing successive stages in the toe lasting of the shoe of Figs. 7 and 8;

Fig. 11 is a sectional view through the toe portion of the shoe of Fig. 10 after it has been removed from the bed lasting machine;

Figs. 12 and 13 are perspective views of insoles prepared in two different manners for the practice of the method of my invention;

Fig. 14 is a perspective view of a shoe embodying the insole of Fig. 12, the upper and insole having been assembled on a last and the toe portion of the upper pulled over preparatory to lasting in accordance with my invention;

Fig. 15 is a transverse sectional view on an enlarged scale through one side of the shoe of Fig. 14, the upper being temporarily secured in lasted position by a tack; and

Fig. 16 is a transverse sectional view through a portion of the insole, the shoe upper and the outsole of the completed shoe made as illustrated in Figs. 14 and 15.

In the manufacture of shoes, as illustrated in Figs. 1 to 6, the shoe upper and insole are prepared in accordance with the practice usual in the manufacture of compo shoes except that the lining of the shoe, and preferably also the doubler, if one be used, is composed of a fabric at least part of the threads of which are of a material readily soluble in a suitable organic solvent. Preferably these threads are composed of a soluble cellulose derivative such as a cellulose ester or ether, for example cellulose acetate. Accordingly, the shoe illustrated in Figs. 1 to 6 is provided with a multi-ply upper comprising an outer layer

5

20

25

30

35

40

55

10 of leather or other suitable material, a doubler 12 and a lining 14, the doubler and lining both being made of a textile fabric part of the threads 16 of which are of cotton or other relatively insoluble 5 material while other threads 18 are of cellulose acetate fibre. The two kinds of threads are indicated diagrammatically on an enlarged scale in Fig. 1 within the circle A, the white threads being of cotton and the stippled threads of cellulose acetate fibre. In this connection it may be 10 worth while to note at this time that the cellulose acetate material at present available under the trade name "Celanese" is well adapted to use for this purpose, though it should be understood that other cellulose esters and ethers may 15 also be used.

As illustrated in Fig. 1, an insole 20 and a shoe upper, which contains, in addition to the layers previously mentioned, a toe box 22 preferably of fabric impregnated with pyroxylin, as disclosed in Letters Patent of the United States No. 1,711,956, granted May 7, 1929, on an application filed in the name of Stanley P. Lovell, and a counter 24 of the same or any other suitable material, have been 20 assembled upon a last 25 in the usual manner after which the upper is pulled over and secured in pulled-over position by the usual tacks, as indicated at 26. The marginal portion of the upper and the forward portion of the counter 24 at approximately the heel breast line may, if desired, 25 be temporarily secured in position by tacks 28 which are to be removed before the sole of the shoe is attached and, therefore, are preferably left with their heads upstanding somewhat from the 30 shoe upper.

The shoe is now ready for the side lasting operation. With this in view, the marginal portion of the lining and doubler of the shoe are treated, 35 between the heel breast line and the pulling over tacks adjacent to the toe of the shoe, with a suitable solvent for the soluble cellulose derivative of the lining and doubler, for example acetone, after which, while the cement formed by the action of the solvent on the cellulose derivative is soft, the upper is worked into lasted relation to the insole and last between the heel breast line and the pulling over tacks in the vicinity of the tip line, and is secured in that relation either by staples, as indicated at 30 in Figs. 2 and 4, or by tacks, as shown 40 at 104 in Fig. 15, which hold the upper in lasted position while the cement is setting. Since these staples or tacks are later to be removed they are 45 preferably left projecting somewhat from the upper for the more ready engagement by a staple or tack pulling tool. If staples are to be used they are preferably driven with their legs deflected and curved back through the insole stock in such a way that they do not pass through to the inside of the shoe. Advantageously, the side lasting operation may be performed with a side lasting machine of the character disclosed in Letters Patent 50 of the United States No. 1,815,297, granted July 21, 1931, on an application filed in the name of George Goddu, the machine being adjusted so that 55 the staples are driven only far enough to leave them with their bars projecting somewhat from the upper material, as disclosed in Fig. 4 (for example) of Letters Patent of the United States No. 1,932,544, granted October 31, 1933, on an application filed in the name of said Goddu.

After the side lasting tacks or staples have been driven the shoe is ready for the toe and heel lasting. This may be advantageously performed with the aid of a bed lasting machine of usual 60 type, as indicated in Fig. 4. The last 25 on which

the shoe is mounted is placed on the last pin 32 of the machine with its toe portion supported by the usual toe rest 34 and the toe band 36 is brought into place in the usual manner. After this the wipers 38 and 40 at the toe end of the machine are operated to wipe the upper in over the insole at the toe end of the shoe. The wipers are then withdrawn and the layers of the upper at the toe separated sufficiently to enable the operator to moisten the fabric of the lining 14 and 10 doubler 12 and of the box toe 22 with acetone or other suitable solvent. It is generally desirable before applying this solvent to trim off any surplus material that may be present in the layers which 15 are to be activated so as to avoid the presence of lumps or bunches which might interfere with the toe lasting operation. After the solvent has 20 been applied the wipers 38 and 40 are again operated to bring the upper into its final lasted condition, the wipers then being backed off just 25 sufficiently to receive a toe binder 42 which, as illustrated, is of the character disclosed in Letters Patent of the United States No. 1,894,678, granted January 17, 1933, on an application filed in the name of Joseph Fausse. The wipers 38 and 40 are 30 then brought forward again with their edges overlying the bottom flange of the binder 42 and a clamp member 44 is applied to the binder and secured to the bottom of the last by a tack 46, as disclosed in Letters Patent of the United States 35 No. 2,004,239, granted June 11, 1935, on an application filed in the name of Isabelle W. Goddu, executrix of the will of George Goddu, deceased.

The heel end of the shoe is then lasted in similar 40 fashion, except that, on account of the longer radius of curvature of the heel end of the shoe than of the toe, it will not ordinarily be necessary to trim away any of the material of the inner layers of the shoe upper. Before lasting the heel seat of the shoe the tacks 28 and whatever assembling tacks have been inserted should be removed. After this the material of the lining and 45 doubler is treated with a solvent such as acetone, as related in connection with the lasting of the toe, and the heel binder 50 is applied and held 50 by the wipers 52 while the clamp member 54 is positioned and secured by the tack 56.

It should be understood that it is in no way 55 essential that the binders 42 and 50 be used since obviously the shoe upper may be held at the toe and heel by other means while the cement sets, for example by tacks as indicated in Fig. 15. Furthermore, if a shoe manufacturer is not 60 inconsistent upon a tackless heel seat the heel end of the shoe may be lasted in the usual manner, with the aid of tacks which remain in the shoe.

After the shoe has been lasted, as illustrated in Fig. 4, it is removed from the bed laster and allowed to rest, for example in the usual rack, until the cement has set. After this the clamps 46 and 65 54 and the binders 42, 50 are removed and the staples 38 or the corresponding tacks and the insole tacks, illustrated at 58 in Figs. 1 and 2, are pulled, thus leaving the shoe in the condition illustrated in Fig. 5, with its bottom entirely free from 70 metallic fastenings of any sort.

The shoe may be finished in any usual or desired 75 manner. Any surplus upper stock is trimmed off, a suitable shank piece and filler inserted, and an outsole attached. Thus, as illustrated in Fig. 6, the shoe is provided with a sheet filler 60 to fill the space bounded by the margin of the upper at the forepart of the shoe and with an outsole 62 attached, as indicated at 64, with the aid of pyroxylin or other suitable cement. Fig. 6 also il-

lustrates the manner in which the cotton or other insoluble threads 16 of the lining and doubler are anchored between the insole 20 and the overlasted marginal portion of the upper leather 10 in the 5 cement formed from the soluble threads 18.

While Fig. 6 illustrates a section through a composite shoe made in accordance with the method of my invention, it should be understood that the invention is also applicable to the manufacture of 10 shoes of other types. Thus the outsole instead of being attached by cement may be attached by through-and-through stitching. Furthermore, it will be apparent that the invention is applicable to use in the manufacture of shoes of other types 15 than those in which the upper is lasted inwardly flat against the surface of an insole. Obviously, it may be applied also to the manufacture of shoes in which the upper is lasted to a ribbed or shoddered insole as well as to shoes of the stitchdown 20 type in which the upper is turned outwardly from the last against the projecting marginal portion of an insole.

Instead of making the whole of the lining, and the doubler if one there be, of fabric of the character described in connection with Figs. 1 to 6, the lining and/or the doubler may be formed of cotton or other relatively insoluble fabric having, as illustrated in Figs. 7 and 8, strips 70, 72, and 74 of soluble fabric secured, as by stitching, to their 30 marginal portions. The shoes of Figs. 7 and 8 are assembled, pulled over and side lasted like the shoes of Figs. 1 to 6 except that the fabric from which the lasting cement is to be formed consists merely of strips in the form of tape, braid or the like stitched, as indicated at 76, to the respective 35 layers of the upper. As illustrated in Figs. 7 and 8 these strips extend merely from the heel breast line forwardly about the toe and back to the heel breast line at the other side of the shoe, the idea being that in this instance the heel seat portion 40 of the shoe is to be lasted with suitable driven fastenings. The toe of this shoe may be lasted in a manner similar to that described in connection with Fig. 4, as illustrated particularly in Figs. 45 9, 10, and 11. This shoe, it will be observed, will differ from that illustrated in Fig. 6 principally in that the lining and doubler of the overlasted marginal portion of the finished shoe are of their original substance. This has been illustrated in 50 Fig. 11 and in the cross sectional portion of Figs. 9 and 10. After the cement at the sides and toe of the shoe has set the toe binder and temporary fastenings will be removed and the shoe finished as desired.

Further variations in the practice of my invention are illustrated in Figs. 12 to 16, inclusive, in which the fabric from which the lasting cement is to be formed is secured to the insole instead of forming a part of or being secured to the shoe 60 upper. Thus, Fig. 12 illustrates an insole 78 having a strip 80 of cellulose acetate fabric secured by stitching 82 to the marginal portion of its upper engaging surface. Since it is intended to use this insole in a shoe the heel seat of which, as 65 well as the sides and toe, is to be cement lasted, the strip 80 is applied to the entire peripheral portion of the insole 78. Fig. 13 illustrates an insole 84 having a strip 86 of cellulose acetate fabric extending only from its heel breast line forwardly about the toe of the insole and back to the heel breast line at the other side of the insole. It will be obvious that if the heel seat portion of 70 the shoe is to be lasted with the aid of driven fastenings which remain in the shoe it will be unnecessary to apply the strip 86 to the marginal por-

tion of the heel seat of the insole. Fig. 13, moreover, illustrates the strip 86 as secured to the insole by spots of cement 88 which may be formed merely by moistening spots on the strip 86 with a suitable solvent, such as acetone, or may be formed by applying pyroxylin or other suitable cement to the insole or to the strip 86. The insole 78 or 84 may be secured to a last by the usual insole tacks 58 and the last and the shoe upper assembled and pulled over, as illustrated in 10 Fig. 14. The shoe upper illustrated in Fig. 14 consists of an outer layer of upper leather 100 and a lining 102, the lasting allowance of the latter being only about half the usual width so that when the shoe is lasted it will project only to 15 about the middle of the strip 80. This permits the overlasted marginal portion of the upper leather 100 to extend beyond the edge of the lining 102 and to have direct contact with the cement formed by the action of a solvent on the soluble 20 cellulose derivative of the strip 80. This will be apparent from a consideration of Fig. 14 and is illustrated in cross section in Fig. 15 in which the shoe upper is illustrated as held in lasted relation by a tack 104 while the cement sets. After the 25 lasting operation has been completed, the cement set, and the temporary fastenings removed, the shoe is completed in any usual or desired manner. Thus is may be provided with a suitable filler at the forepart, as illustrated at 106 in Fig. 16, and 30 the outsole 108 attached by cement, as indicated at 110, or in any other suitable manner.

Having thus described my invention, what I claim as new and desire to secure by Letters Patent of the United States is:

1. A shoe having an upper the marginal portion of which consists at least in part of threads composed of a substance which by solution in an organic solvent forms cement, the upper being secured in lasted relation to the insole of the shoe by cement formed by the action of said organic solvent on the soluble material of the overlasted portion of the upper.

2. A shoe having a multi-ply upper the lining of which is composed of a fabric at least part of the thread of which is of a substance which by solution in an organic solvent forms cement, the upper being secured in lasted relation to the insole of the shoe by cement formed by the action of said organic solvent on the material of the marginal portion of the lining.

3. A shoe having a multi-ply upper the lining of which is composed of a fabric at least part of the thread of which is composed of a cellulose ester or ether, the upper being secured in lasted relation to the insole of the shoe by cement formed by the action of an organic solvent on the material of the cellulose ester or ether threads at the marginal portion of the lining.

4. A shoe having a multi-ply upper the lining of which consists of a fabric a substantial part at least of the thread of which is composed of cellulose acetate, the upper being secured in lasted relation to the insole of the shoe by cement formed by the action of an organic solvent on the cellulose acetate of the threads of the marginal portion of the lining.

5. A shoe having a multi-ply upper the lining of which is composed of a fabric part of the thread of which is of a substance which by solution in an organic solvent forms cement and the remainder of which is insoluble in said solvent, the upper being secured in lasted relation to the insole of the shoe by cement formed by the action of said organic solvent on the material of the

- soluble threads at the marginal portion of the lining.
6. That improvement in methods of manufacturing shoes which comprises assembling an insole and an upper upon a last, the shoe upper having a strip of a readily soluble cellulose derivative secured to the insole engaging surface of its lasting allowance, treating the cellulose derivative with a solvent therefor and thereby forming cement, working the upper into lasted relation with the insole and last with said cement between the insole and the overlasted portion of said upper, and holding the upper in lasted relation to the insole while the cement sets.
- 10 7. That improvement in methods of manufacturing shoes which comprises working the marginal portion of a shoe upper into lasted relation to an insole and last with cement, formed by treating a strip of fabric composed of a readily soluble cellulose derivative with a solvent therefor, between the insole and the overlasted portion of the upper, and holding the upper in lasted relation to the insole and last while the cement sets.
- 15 8. That improvement in methods of manufacturing shoes which comprises assembling upon a last an insole and a multi-ply shoe upper the marginal portion of the lining of which is provided with threads of readily soluble material which upon solution in a suitable solvent forms cement, treating the marginal portion of the lining with said solvent and thereby dissolving said soluble material and forming cement, working the upper into lasted relation to the insole and last, and securing the upper temporarily in lasted relation while said cement sets.
- 20 9. That improvement in methods of manufacturing shoes which comprises assembling upon a last an insole and a multi-ply shoe upper the marginal portion of the lining of which consists of a fabric part at least of the thread of which is of material readily soluble in an organic solvent and which by dissolving in said solvent, forms cement, treating the marginal portion of the lining with said solvent and thereby dissolving the soluble material of the upper and forming cement, working the upper into lasted relation to the insole and last, and securing it temporarily in lasted relation while said cement sets.
- 25 10. That improvement in methods of manufacturing shoes which comprises assembling upon a last an insole and a multi-ply shoe upper the marginal portion of the lining of which consists of a fabric part of the thread of which is of material readily soluble in an organic solvent and which, by solution in said solvent, forms cement and part of the thread of which is of material insoluble in said solvent, treating the marginal portion of the lining with said solvent and thereby dissolving the soluble material of the upper and forming cement, working the upper into lasted relation to the insole and last, and securing it temporarily in lasted relation while said cement sets.
- 30 11. That improvement in methods of manufacturing shoes which comprises assembling an insole and a shoe upper on a last, the marginal portion of one of said shoe parts being provided with a strip of fabric comprising threads of material which is soluble in an organic solvent thereby forming cement, treating said fabric with said solvent and, by its action on the soluble threads, forming cement, working the upper into lasted relation to the insole and last with said cement between the insole and the overlasted portion of said upper, and inserting temporary fastenings to hold the upper in lasted relation to the insole and last while the cement sets.
- 35 12. That improvement in methods of manufacturing shoes which comprises assembling an insole and a shoe upper on a last with a strip or strips of fabric composed of a readily soluble cellulose derivative stitched to the marginal portion of one of said shoe parts, applying to the soluble fabric a solvent therefor and, thereby forming cement, working the upper into lasted relation to the insole and last, and holding the upper in lasted relation to the insole and last while said cement sets.
- 40 13. That improvement in methods of manufacturing shoes which comprises assembling upon a last an insole and a multi-ply upper having a doubler and lining composed of a fabric comprising threads which are soluble in an organic solvent and, when dissolved by said solvent, forms cement and threads which are insoluble in said solvent, treating the marginal portion of the lining and doubler with said solvent and, by its action on the soluble threads, forming cement, working the upper into lasted relation to the insole and last, and driving fastenings through the upper and into the insole to hold the upper in lasted relation while said cement sets.
- 45 14. That improvement in methods of manufacturing shoes which comprises stitching a strip of fabric composed of a readily soluble cellulose derivative to the inner surface of the marginal portion of a shoe upper, assembling the upper and an insole on a last, applying to the soluble fabric a solvent therefor and thereby forming cement, working the upper into lasted relation to the insole and last, and holding it in lasted relation while said cement sets.
- 50 15. That improvement in methods of manufacturing shoes which comprises stitching strips of fabric composed of a readily soluble cellulose derivative to the inner surface of the marginal portions of the various layers of a multi-ply shoe upper, assembling the upper and an insole on a last, applying to the soluble fabric a solvent therefor and thereby forming cement, working the upper into lasted relation to the insole and last, and inserting temporary fastenings to hold it in lasted relation while said cement sets.
- 55 16. That improvement in methods of manufacturing shoes which comprises applying to the upper engaging surface of an insole a strip of cellulose ester fabric and securing the strip to the insole by cement formed by treating portions of the strip with a solvent for said cellulose ester, assembling said insole and a shoe upper on a last, treating the strip of cellulose ester fabric with a solvent therefor and thereby forming cement, and working the shoe upper into lasted relation to the insole and last and holding it in lasted relation while said cement sets.
- 60 17. That improvement in methods of manufacturing shoes which comprises applying to the upper engaging surface of an insole a strip of cellulose acetate fabric and securing the strip to the insole by cement formed by treating portions of the strip with an organic solvent for cellulose acetate, assembling said insole and a shoe upper on a last, treating the strip of cellulose acetate fabric with a solvent therefor and thereby forming cement, and working the shoe upper into lasted relation to the insole and last and securing it temporarily in lasted relation while said cement sets.
- 65 18. That improvement in methods of manufac-

- turing shoes which comprises securing to the marginal portion of the upper engaging surface of an insole a strip of material which, upon treatment with a suitable solvent, forms cement, assembling upon a last said insole and a shoe upper the outer layer of which has a normal lasting allowance and the inner layer or layers of which has a lasting allowance substantially narrower than that of the outer layer, treating the strip of fabric on the insole with said solvent thereby forming cement, working the upper into lasted relation to the insole and last, and inserting temporary fastenings to hold it in that relation while said cement is setting.
- 15 19. That improvement in methods of manufacturing shoes which comprises stitching to the marginal portion of the upper engaging surface of an insole a strip of fabric composed of material which, upon treatment with a suitable solvent, forms cement, assembling upon a last said insole and a shoe upper the outer layer of which has a normal lasting allowance and the inner layer of which has a lasting allowance about half the width of that of the outer layer, treating the strip of fabric on the insole with said solvent and thereby forming cement, working the upper into lasted relation to the insole and last and driving temporary fastenings to hold it in that relation while said cement is setting.
- 20 20. A shoe upper the lasting allowance of which is provided at its inner surface with textile fabric at least a part of the thread of which is composed of a cellulose derivative readily soluble in an organic solvent.
- 25 21. A multi-ply shoe upper the lasting allowance of the inner layer or lining of which is provided with a substantial quantity of material in the form of threads of material readily soluble in an organic solvent and which, upon solution in said solvent, forms cement.
- 30 22. A multi-ply shoe upper the lasting allow-

- ance of the inner layer or lining of which consists of a fabric composed at least in part of threads of material soluble in an organic solvent and which, upon solution in said solvent, forms cement.
23. A multi-ply shoe upper the inner layer or lining of which consists of a fabric composed at least in part of threads of material soluble in an organic solvent and which, upon solution in said solvent, forms cement.
24. A shoe upper having a strip of fabric, the threads of which are composed of a cellulose derivative readily soluble in an organic solvent, stitched to its lasting allowance.
25. An insole having a strip of material secured to the marginal portion of its upper engaging surface, said material comprising a fabric the threads of which consist at least in part of material readily soluble in an organic solvent.
26. An insole having a strip of material stitched to the marginal portion of its upper engaging surface, said material comprising a fabric the threads of which consist at least in part of a cellulose derivative readily soluble in an organic solvent.
27. An insole having a strip of material stitched to the marginal portion of its upper engaging surface, said material comprising a fabric the threads of which consist at least in part of cellulose acetate.
28. An insole having a strip of fabric, the threads of which consist at least in part of a cellulose ester or ether, secured to its marginal portion by cement formed by the action of a solvent on the cellulose ester or ether of the fabric.
29. An insole having a strip of cellulose acetate fabric secured to its marginal portion by cement formed by the action of a solvent on the cellulose acetate of the threads of the fabric.

MAX W. TETLOW. 40
